UNITED STATES PATENT OFFICE.

CHARLES J. PILLIOD, OF TOLEDO, OHIO.

INTERNAL-COMBUSTION ENGINE.

1,178,672.

Specification of Letters Patent. Patented Apr. 11, 1916.

Application filed April 19, 1915. Serial No. 22,451.

To all whom it may concern:

Be it known that I, CHARLES J. PILLIOD, a citizen of the United States of America, residing at Toledo, in the county of Lucas 5 and State of Ohio, have invented certain new and useful Improvements in Internal-Combustion Engines, of which the following is a specification, reference being had therein to the accompanying drawings.

10 The invention relates to internal combustion engines, and has for its object the obtaining of a construction of balanced valve, which is completely protected from the excessive internal heat, and which is a construction that can be readily manufactured 15 and is efficient in its operation.

With these objects in view the invention comprises the construction as hereinafter set forth.

20 In the drawings: Figure 1 is a longitudinal section through the engine cylinder and valve case; Fig. 2 is a cross section thereof; and Fig. 3 is a section on line $x-x$ Fig. 1.

A is the engine cylinder surrounded by 25 the usual water jacket B.

C is a cylindrical valve case having its axis arranged parallel to the axis of the cylinder and preferably formed integral therewith, said case being also provided with a 30 surrounding water jacket D.

E is a detachable central core member 35 within the case C, which is centrally provided with a combustion chamber F communicating with the combustion chamber within the cylinder A through registering ports G and G'. Surrounding this combustion chamber F and between the same and the outer wall of the core is a water jacket H, which communicates with the outer water 40 jacket through registering ports I and I'.

J is a hollow cylindrical valve arranged in the space between the core member E and the valve case C, and which as shown is of the longitudinally reciprocatory type. 45 There is also as shown a second cylindrical valve J' for coöperation with the valve J, together therewith controlling inlet and exhaust ports K and K' on opposite sides of the case. The water chambers which are adjacent to the walls of the core and the cylindrical case C completely protect the same from the internal heat of the engine, while the valve J and J' are also protected by the water-cooled walls throughout their entire 55 extent. Consequently difficulties in lubrication are avoided as well as any warping or

distortion which might result from excessive heat.

It is desirable to employ piston rings in connection with the reciprocating sleeve 60 valves, and I have therefore provided a series of rings L L', etc. To facilitate the manufacture these rings are all placed in grooves in the detachable core section E, and may therefore be assembled before this 65 section is placed within the valve case. To prevent leakage from the ports crossing the joint between the outer casing and the core a series of annular packings are provided, and to insure the permanence of 70 these packings the core and outer case are stepped to form shoulders M M' M². The shoulders M and M' are upon opposite sides of the ports G and G', which connect the combustion chamber in the cylinder with the combustion chamber within the hollow core. The packings M' and M² are upon opposite sides of the ports I I' which connect the outer water jacket with the water chamber within the core. Thus 80 both the leakage of the gases of combustion and the cooling water is prevented. The spark plug N is preferably arranged in the core member E, so that ignition takes place within the chamber F. There is also preferably provided a priming cup O which 85 communicates with the chamber F.

In operation, the valves J J' are operated in properly timed sequence by any suitable mechanism, such as pitman connections P 90 engaging a crank or eccentric shaft (not shown). During their operation the valves are completely protected by the water chambers in the inner core of the outer jacket, so that there is no danger of carbonization of 95 the lubricant.

What I claim as my invention is:

1. In an internal combustion engine, the combination with the cylinder, of a cylindrical valve case arranged substantially 100 parallel thereto, inter-connected surrounding water jackets for said cylinder and valve case, a core section detachably engaging said valve case, comprising an inner combustion chamber, a surrounding water jacket 105 and ports establishing communication respectively between said combustion chamber and the engine cylinder and between the water jacket of the core and the external water chamber, and a cylindrical sleeve 110 valve intermediate said core and outer valve case controlling ports therein.

2. In an internal combustion engine, the combination with a cylinder, of a cylindrical valve case at the side thereof, a water jacket for said cylinder and valve case, a detachable 5 cylindrical core within said valve case having a central combustion chamber, a surrounding water jacket and ports for connecting said combustion chamber and water jacket respectively with the combustion 10 chamber of the cylinder and external water jacket, and an annular packing in the joint between the core and valve case for preventing leakage from said ports.
3. In an internal combustion engine, the 15 combination with a cylinder and a valve case at one side thereof, of a detachable core within said valve case having a central combustion chamber and a surrounding water jacket and ports crossing the joint between 20 said core and outer case for establishing communication between said combustion chamber in the core and engine cylinder and between the water space in the core and external water jacket, and packing means for 25 the joint between said core and outer case surrounding the ports therethrough.
4. In an internal combustion engine, the combination with a cylinder, of an adjacent cylindrical valve case at one side thereof and 30 a surrounding water jacket all integrally formed, a detachable cylindrical core within said valve case having a portion spaced therefrom to form an annular recess for the valve and a portion fitting said case, said 35 core also having a central combustion chamber, a surrounding water jacket and ports crossing the joint between the core and case and respectively establishing communication between said combustion chamber and engine 40 cylinder and between the internal and external water jackets, and means for packing the joint surrounding the ports crossing the same.
5. In an internal combustion engine, the 45 combination with an engine cylinder, of an adjacent cylindrical valve case at one side thereof, a detachable core member within said valve case having a cylindrical portion of lesser diameter forming an annular space 50 for the valve and a larger cylindrical por-

tion having a stepped engagement with said case, said core being further provided with a central ported combustion chamber, a water jacket surrounding said combustion chamber and ports crossing the joint for establishing communication between said combustion chamber and the cylinder and between the internal and external water jackets, said latter ports being separated from each other, the valve chamber and external atmosphere by steps, and packing for said steps to seal the joint on opposite sides of said ports.

6. In an internal combustion engine, the combination with a cylinder, of a cylindrical valve casing at one side thereof and a surrounding water jacket, a detachable core for said valve case having a cylindrical portion of lesser diameter forming an annular valve chamber and a portion fitting said case provided with a stepped or shouldered engagement therewith, said core also having a central combustion chamber, a surrounding water jacket and ports connecting said combustion chamber and cylinder and internal and external water jackets, said ports being between steps, and packing arranged upon said steps.

7. In an internal combustion engine, the combination with a cylinder, of a cylindrical valve casing adjacent thereto, a cylindrical core member within said valve casing having a portion of lesser diameter forming an annular chamber for the valve and a portion fitting said valve case, said core having also a central ported combustion chamber communicating with said cylinder and a surrounding water jacket, a cylindrical sleeve valve in the chamber between said core and valve casing controlling the ports of said central combustion chamber, and annular packing rings engaging grooves in said core member upon opposite sides of said ports.

In testimony whereof I affix my signature 95 in presence of two witnesses.

CHARLES J. PILLIOD.
